STOCKING FORM

Filed July 8, 1922

2 Sheets-Sheet 2

UNITED STATES PATENT OFFICE.

JOHN L. FAGAN, OF PHILADELPHIA, PENNSYLVANIA, ASSIGNOR TO PROCTOR & SCHWARTZ, INCORPORATED, OF PHILADELPHIA, PENNSYLVANIA, A CORPORATION OF PENNSYLVANIA.

STOCKING FORM.

Application filed July 8, 1922. Serial No. 573,751.

To all whom it may concern:

Be it known that I, JOHN L. FAGAN, a citizen of the United States, residing in Philadelphia, Pennsylvania, have invented 5 certain Improvements in Stocking Forms, of which the following is a specification.

One object of my invention is to improve the construction of forms used in drying stockings so that stockings can be readily 10 placed upon the forms and removed therefrom without undue stretching of the fabric of the stockings.

A further object of the invention is to make the foot portion of each form removable so that foot portions of different sizes 15 can be used in connection with the standard body portion of the form.

The invention is especially adapted for use in connection with drying machines where 20 the stockings are placed on the forms by hand—automatic means being used to remove them from the forms.

In the accompanying drawings:

Fig. 1 is a side view of a stocking form 25 illustrating my invention;

Fig. 2 is a view with one of the side plates removed and a stocking form in the position which it assumes when a stocking is being removed from the form;

Fig. 3 is a longitudinal, sectional view on the line 3—3, Fig. 1;

Fig. 4 is a sectional view on the line 4—4, Fig. 1;

Fig. 5 is a perspective view of the upper 35 portion of the body of a form;

Fig. 6 is a detached perspective view of one of the foot portions;

Fig. 7 is a side view of a stocking form illustrating a modification of the invention;

Fig. 8 is a view, similar to Fig. 7, showing the foot portion raised; and

Fig. 9 is a sectional view on the line 9—9, Fig. 7.

Referring to the drawings, 1 is the body 45 of a stocking form on which the leg of a stocking is stretched. Rigidly secured to the body portion are thin plates 2, which are held by screws, rivets, or other fastenings 3. The body portion is cut away in a 50 peculiar manner, as clearly shown in Fig. 5, which forms a recess 4 for the reception of the inner end of the foot portion 5. This foot portion 5 is pivoted to the body portion by a pivot pin 6, which, in the present 55 instance, is mounted on a spring tongue 7,

forming an integral part of one of the plates 2. This pivot pin 6 extends through an opening 8 in the foot portion 5 and into an opening in the opposite plate 2, as clearly shown in Fig. 3. By forcing the pivot pin 60 out against the pressure of the spring, the foot portion can be removed and another one of a different size can be substituted for it, if desired.

The body portion is shaped to form the 65 heel section 9 and has an extension 10. The foot portion is slotted at 11 to receive the extension 10 when the foot portion is moved from the position shown in Fig. 1 to that shown in Fig. 2. By this construction, the 70 slot, in which the foot portion works, is covered, preventing a stocking from being caught in the moving parts of the form.

In order to hold the foot portion normally in the position shown in Fig. 1, in addition 75 to the weight of the foot portion, a spring 12 is provided, which, in the present instance, is U-shaped in form and is located in the slot 4 back of the foot portion so that, when the foot portion is moved to the position shown in Fig. 2, on the withdrawal of the stocking, the foot portion will be returned immediately to its first position, as shown in Fig. 1.

In Figs. 7, 8 and 9, a modification of the 85 invention is illustrated, in which the foot portion 5^a is pivotally mounted on one side of the body portion 1^a—both the body portion and the foot portion being recessed, as clearly shown in Fig. 9, so that the thickness 90 of the form is not increased at the pivot point.

In order to limit the movement of the foot portion 5^a, a slot 13 is formed in the body portion into which extends a pin 14 on the 95 foot portion so that, when the foot portion is moved to the position shown in Fig. 8, the pin travels in the slot. The limit of movement is dependent upon the length of the slot. In this case, the foot portion returns 100 to its original position by its own weight, although, if found desirable, a spring may be provided.

The operation is as follows: When the 105 stocking forms are used in connection with a drying machine in which automatic means are employed to remove a stocking from a form, the operator manually places a stocking on a form in the usual manner. If found desirable, the operator can raise the foot 110

portion to the position shown in Fig. 2, which allows the stocking to be placed correctly on a form without materially stretching the fabric. The foot form then assumes 5 the position shown in Fig. 1. The form, with the stocking thereon, is then carried into a drier of any suitable construction. When the stockings are dried, they are removed from the drier by automatic means 10 provided for engaging the toe and heel portion of each stocking while the form is being withdrawn. During this operation, the foot portion assumes the position shown in Fig. 2, so as to prevent unnecessary stretching of 15 the fabric as a form is removed from a stocking.

When the device is used on a machine in which the stockings are removed by hand, the operator—on removing a stocking from 20 a form—turns the foot portion to the position shown in Fig. 2, thus preventing any undue stretching of the fabric of the stocking.

I claim:

25 1. The combination in a stocking form, of a flat body portion; and a foot portion pivotally mounted on the body portion so as to be rotatable with the plane thereof, said pivot being supported by a portion of the body 30 and detachably engaging the foot portion so that a foot portion can be removed from the body portion and another foot portion substituted therefor.

2. The combination in a stocking form, of

a flat body portion shaped at one end to form 35 a recess, two walls of the recess forming stops; a thin side plate secured to each side of the body portion and extending on each side of the recess; and a flat foot portion extending into the recess; and a pivot connecting the foot portion with the body portion so that the foot portion is free to rotate in the plane of the body portion.

3. The combination in a stocking form, of a body portion recessed at one end; side 45 plates rigidly secured to the body portion and closing the recess at each side; a spring tongue on one of said plates; a pivot carried by the tongue; and a foot portion extending into the recess between the plates and having 50 a pivot opening into which the pivot extends.

4. The combination in a stocking form, of a body portion recessed at one end; side 55 plates secured to the body portion and extending on each side of the recess; and a foot portion extending into the recess and pivotally mounted on the side plates, the body portion having an extension at the end, and the foot portion having a slot to allow for 60 the reception of the extension of the body portion when the foot portion is moved from its normal position.

5. The combination in a stocking form, of a body portion; a foot portion pivotally mounted on the body portion; and a spring 65 tending to hold the foot portion in its normal position at an angle to the body portion.

JOHN L. FAGAN.
